J. V. Van Tuyl

Wind Wheel.

Patented Sep. 28, 1831.

John G. Van Tuyl
Sectress Patent

6772 X

The Schedule, referred to in these Letters Patent, and, making part of the same, containing a description in the words of the said John G. Van Tuyl himself, of his improvement in the application of the Power of Wind to Mills, Factories, Boats or Ropels, Pumps and all kinds of Machinery.

To all to whom these presents shall come:

Be it known that I, John G. Van Tuyl, of Rahway in the County of Essex and State of New Jersey, have invented a new and useful improvement in the application of the power of Wind, applicable to Mills, Factories, Boats or Ropels, Pumps and all kinds of Machinery, requiring power, and that the following is a full and exact description of the construction and operation of the said improvement as invented by me (a drawing, of which is annexed) vizt

In the centre is an upright shaft running on a pivot in the ordinary manner. The wheel is made as common water wheels with the buckets outside of the rims, and of course run horizontally. The rod line is intended to represent an open space just wide enough for the buckets to close the ends of the funnel boards. The funnels are represented by the angular lines drawn around the wheel, and are made firmly fast on a circular floor of sufficient width for the length of the funnel. The buckets or propelling boards are secured to the wheel at right angles with the wheel, of any required length outside the rims, on which the wind acts, being driven thro' the funnels and discharged on the buckets at the throat of the funnels where it is compressed and acquires a greatly increased force. The rim of the wheel must be as broad as the buckets are long and made tight to prevent the wind escaping.

7/20/1031 0112X
ing into the wheel. The buckets are straight pieces of board
set with a small inclination to receive the wind direct from
the throat of the funnel. The funnels must be as deep perpendicular-
ly at the throat as the length of the buckets and all placed
on the same angle from the axis of the wheel, and covered with
a cover corresponding with the floor. The size of the mouths of
the funnels will be in proportion to the length of the funnels,
which can be regulated according to the force or resistance
required to be overcome and the power can be increased to any
desired extent. Doors must be hung at the mouth of every
funnel, for the purpose of closing as many of the funnels as may
be necessary, when the wind is too strong to open back against
a cleat at top and bottom, and can be opened or shut by a
cord or chain leading through pulleys or blocks into the mill
and the motion of the wheel thereby regulated at pleasure,
in connection with a Governor & friction bands. The Invention
claims in the improved manner above described for applying
the power of Wind to Mills &c - which I believe to be origin-
al
